GAME BOARD OR ANALOGOUS ARTICLE

Permil N. Nelson, P.O. Box 505, Galesburg, Ill.

Filed May 21, 1959, Ser. No. 56,013

Term of patent 14 years

(Cl. D34—5)

FIG. 2.

FIG. 1.

Fig. 1 is a front elevational view of the game board; and

Fig. 2 is a side view thereof.

The dominant features of my invention reside in those portions shown in full lines on the drawing.

I claim:

The ornamental design for a game board or analogous article, as shown and described.
